CLAIM

The ornamental design for a double back frame chair back as shown and described.

DESCRIPTION

FIG. 1 is a front elevation view of a double back frame chair back showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a front perspective view thereof.

The broken lines in the figures depict portions of the double back frame chair back that form no part of the claimed design.
